UNITED STATES PATENT OFFICE.

HOMER W. POTTER, OF DETROIT, MICHIGAN.

FIRE-CRACKER PISTOL.

SPECIFICATION forming part of Letters Patent No. 766,286, dated August 2, 1904.

Application filed November 12, 1903. Serial No. 180,830. (No model.)

to all whom it may concern:

Be it known that I, HOMER W. POTTER, a citizen of the United States, residing at Detroit, in the county of Wayne and State of Michigan, have invented certain new and useful Improvements in Fire-Cracker Pistols, of which the following is a specification.

The object of my invention is to produce a cheap holder for fire-crackers into which the fire-cracker body may be readily introduced, from which it cannot be readily accidentally dropped, and from which it can be forcibly expelled.

The accompanying drawings illustrate my invention.

Figure 1 is a side elevation. Fig. 2 is a central vertical section; Fig. 3, a perspective view of the plunger, and Fig. 4 a section on line 4-4 of Fig. 1.

In the drawings, 10 indicates a main body having barrel 11, in the upper wall of which is formed a longitudinal slot 12. Body 10 and barrel 11 will in practice be preferably made in two halves secured together in any suitable manner. The slot 12 extends clear to the forward end of the barrel, and mounted in the barrel is a suitable plunger 13, behind which is arranged a propelling-spring 14. Plunger 13 is provided with a finger-piece 15, which projects outward through slot 12, and the plunger may be retained in its rear position, with the spring compressed, by means of a suitable trigger 16. Plunger 13 is also provided with a finger 17, which passes into the end of spring 14. Thus far the mechanism is substantially old, except that the slot 12 ex-

tends clear to the forward end of the barrel. With such a structure a fire-cracker can be introduced into the barrel and its fuse hung out through the slot 12; but if the barrel happened to be slightly inclined downward the cracker would fall out. I therefore form in one side of barrel 11 a transverse slot 18, which connects with slot 12 and into which the fuse 19 may be drawn at right angles to the barrel 11, thus locking the cracker in the barrel.

In operation the fuse may be lighted, and when it has burned down close to the barrel 11 the trigger 16 may be pulled and the cracker thereupon forcibly expelled from the pistol 50 into the air, where it will explode.

I claim as my invention—

1. A fire-cracker pistol consisting of a hollow receiving-barrel, suitable propelling mechanism arranged therein, and a transverse retaining-slot 55 through which the fire-cracker fuse may be projected.

2. A fire-cracker pistol consisting of a main body, and a tubular receiving-barrel having a longitudinal slot extending to the end thereof, suitable propelling mechanism arranged in the barrel, and a transverse slot formed in the barrel and communicating with the longitudinal slot through which transverse slot the fire-cracker fuse may project. 65

In witness whereof I have hereunto set my hand and seal, at Indianapolis, Indiana, this 10th day of November, A. D. 1903.

HOMER W. POTTER. [L. S.]
